UNITED STATES PATENT OFFICE.

TIM PENWELL AND HARRY E. BROWN, OF ELDORADO, KANSAS.

ADJUSTER.

1,367,426.

Specification of Letters Patent.

Patented Feb. 1, 1921.

Application filed November 16, 1918. Serial No. 262,893.

To all whom it may concern:

Be it known that we, TIM PENWELL and HARRY E. BROWN, citizens of the United States, residing at Eldorado, in the county of Butler, State of Kansas, have invented a new and useful Adjuster, of which the following is a specification.

The subject of this invention is an adjuster for the polished rod of an oil pump.

10 A main object of the invention is the provision of an adjuster which will not score or injure the polished rod.

Another object of the invention is the provision of means for drawing the polished rod into adjusted positions.

15 The invention also contemplates generally improving the construction and enhancing the utility of adjusters.

With the foregoing and other objects in view, which will appear as the description proceeds, the invention resides in the combination and arrangement of parts and in the details of construction hereinafter described and claimed, it being understood 20 that changes in the precise embodiment of the invention herein disclosed can be made within the scope of what is claimed without departing from the spirit of the invention.

25 A practical structure for carrying out the invention is shown in the accompanying drawing, wherein:—

Figure 1 is a view in side elevation of an adjuster constructed in accordance with the invention, the same shown in place on 30 the end of a walking beam;

Fig. 2 is a view in front elevation of the same;

Fig. 3 is a bottom plan view of the adjuster, remote parts removed;

40 Fig. 4 is a plan view of a modified form of clamp;

Fig. 5 is a side elevation of the same;

Fig. 6 is a plan view of a further modification of the clamp;

45 Fig. 7 is a view in side elevation of the same.

Referring to the drawing by numerals of reference:—

A fragment of the usual walking beam 50 through which the pump of an oil well is operated is shown at 1, and upon the beam is mounted the adjuster board 2, which is held in place by the usual T-bolt 2'. The ends of the walking beam and adjuster board are bifurcated and grooved in the usual manner for the reception of the head

of the adjuster and its trunnions, respectively.

The adjuster consists in a head 5, formed with an eye 5' in which a hook may be inserted for the purpose of handling the adjuster. The head 5 has trunnions 4 which rest in the alining grooves formed in the beam and board and support the adjuster.

Secured to the head 5 in any suitable manner, and depending therefrom, is a hollow rod 6 which is formed with a longitudinal slot 7. The slot 7 slidably receives the apertured lug 8 which is swiveled or otherwise secured to the head end of the polished rod 9, which rod is slidable in the hollow rod 6.

The extending apertured lug 8 permits a hook or rope to be attached thereto so that the polished rod may be moved to various 75 adjusted positions without it being necessary for the workmen to mount the walking beam. As this beam is a considerable distance above the derrick floor, a large amount of time is lost in adjusting the rod, and the 80 operation is accompanied by more or less danger to the workmen.

On the lower end of the hollow rod 6 is mounted a U-shaped clamp 10 which straddles the rod 6, and the extending ends of 85 which may be drawn together by a clamping screw 11 for the purpose of actuating the clamp 10 to compress the end of the hollow rod 6 and bind it firmly against the polished rod 9. A set screw 12 is threaded 90 into one of the extending ends of the clamp 10, with its end adapted to thrust against the other extending end of the clamp and force the ends apart and open the clamp. A portion, 13, of the yoke of the clamp is made 95 thin so that the clamp may be readily sprung.

In the modified form of clamp shown in Figs. 4 and 5, the clamp comprises clamping bars 10^a, which are drawn together at one 100 end by the clamping bolts 11^a and, at the other end, by the clamping bolts 13^a.

In the form shown in Figs. 6 and 7, the clamp comprises bars 10^b, which are hinged together at 13^b, and may be drawn together 105 at their other ends by the clamping bolts 11^b.

From the foregoing it will be seen that there is no holding device which will score or mar the polished rod and cause leakage about the same where it passes through the 110 stuffing box.

It is thought that the operation of the de-

vice will be amply apparent from the foregoing description without an extended and special explanation thereof.

Having described our invention, what we claim as new and seek by Letters Patent, is:—

An adjuster of the class described, comprising a head, a tube having one of its ends received in the head, the other end of the tube having a single longitudinal slot defining compressible arms, the edges of the slot being parallel throughout the entire length of the slot, the slot terminating short of the head, a polished rod in the tube between the arms, a clamp comprising approximately parallel members having seats receiving the arms of the tube and located nearer to one end of the clamp than to the other end thereof, means for connecting said members at that end of the clamp which is nearest to the seats, a tightening device connecting said members at that end of the clamp

which is most remote from the seats, and a thrust element coöperating with said members and located between the tightening device and the seats, the thrust element constituting means for opening the clamp, the polished rod being provided with an outstanding lug received slidably in the slot when the clamp is opened by the thrust element, the lug being of sufficient width to be gripped between the arms when the clamp is contracted by the tightening device, the lug having an opening whereby the rod may be suspended when the clamp is loosened.

In testimony that we claim the foregoing as our own, we have hereto affixed our signatures in the presence of two witnesses.

TIM PENWELL.
HARRY E. BROWN.
